UNITED STATES PATENT OFFICE.

MAURICE H. DWORKIN, OF NEW YORK, N. Y.

DESIGN FOR AN ELECTRICAL-FIXTURE BOWL.

60,224.

Specification for Design.

Patented Jan. 17, 1922.

Application filed April 19, 1921. Serial No. 462,721. Term of patent 3½ years.

To all whom it may concern:

Be it known that I, MAURICE H. DWORKIN, a citizen of the United States, residing at New York, borough of Manhattan, in the county and State of New York, have invented a new, original, and ornamental Design for an Electrical-Fixture Bowl, of which the following is a specification, reference being had to the accompanying drawings, forming part thereof.

Figure 1 is a vertical diametrical section; and

Figure 2 is an inverted plan view of the fixture.

What I claim is:

The ornamental design for an electrical fixture bowl as shown.

MAURICE H. DWORKIN.
